John B. Wheeler

United States Patent Office.

JOHN B. WHEELER, OF NEVILLE, OHIO.

Letters Patent No. 80,257, dated July 21, 1868.

IMPROVEMENT IN ENVELOPES.

The Schedule referred to in these Letters Patent and making part of the same.

TO ALL WHOM IT MAY CONCERN:

Be it known that I, JOHN B. WHEELER, of Neville, in the county of Clermont, and State of Ohio, have invented a new and useful Improvement in Fasteners for Envelopes; and I do hereby declare that the following is a full, clear, and exact description thereof, reference being had to the accompanying drawings.

The nature of my invention consists in so constructing and applying my fastener for envelopes as to effectually prevent the opening thereof after it is fastened by my device, without cutting, tearing, or otherwise mutilating the same.

To enable others skilled in the art to which it appertains to make and use my invention, I describe it as follows, viz:

I take a sheet of any desired kind of metal, and of any suitable thickness, preferring, of course, a very thin sheet, say about the one-fortieth ($\frac{1}{40}$) or one-fiftieth ($\frac{1}{50}$) of an inch, and from the same I cut the piece A, Figures 1, 2, 3, about one-half inch square, as shown enlarged in fig. 1. I then cut slits in it, as shown in dotted lines at *a a a a*, fig. 1. Along the red dotted lines I turn the plate up and over on itself, until the edges meet at *b*, figs. 2 and 3, thus forming an opening or mortise through it, a section of which is seen at *c*, figs. 3 and 7. At about one-eighth ($\frac{1}{8}$) of an inch from the end of this mortise, next to the flange *d*, and on one of its inner edges, I form a notch or catch, *e*, Figure 4.

I then cut from the same sheet as above mentioned a piece about one-eighth ($\frac{1}{8}$) of an inch wide at and near its centre, and about three-fourths ($\frac{3}{4}$) of an inch long, the ends tapering to a point, as seen at *f*, Figure 5. To the centre or middle of this piece I attach a small V-shaped spring, *g*, fig. 5. This spring is of such a thickness as to pass freely into the mortise *c* of figs. 3 and 7, and when this spring is inserted and forced home in the said mortise, the end of the spring *g* passes the notch or catch *e* on the inner edge of the same, and takes hold thereof, and thus its retraction is prevented.

The manner of attaching my device to envelopes is as follows, viz:

I attach the piece B, to which the spring *g* is fastened, to the lappel *h*, fig. 6, of the envelope, which is the part on which the mucilage is usually placed; and this I do by passing the spring *g* through the said lappel, and then turning the same down inwards and over the flange or plate to which the spring is attached, as seen at *i*, Figure 6, and securing the same after turning down by the use of mucilage.

I then attach the part A, figs. 2 and 6, to the body of the envelope, in such position as that, when the same is to be closed, and the spring *g* of the piece B, which is attached to the lappel as shown, is forced home in the mortise of A, the envelope will be neatly closed. This piece A is fastened to the envelope by turning up the two corners *k k*, figs. 2 and 7, of the plate, at right angles thereto, and then passing said corners through the paper or material of which the envelope is made, and then turning down the said corners on the same, as seen at *k k*, fig. 7.

It will be seen from the foregoing that when my device is made and attached to the envelope, and used as described, the envelope cannot be opened without mutilation.

Having fully described the construction and use of my invention, I claim, and desire to secure by Letters Patent—

1. The piece or device A with its mortise *c* and notch or catch *e* in same, in combination with the piece B and its spring *g*, substantially as shown and described.
2. The manner of fastening the pieces A and B to the envelope, and securing the same from being opened without mutilation, substantially as shown and described.

JOHN B. WHEELER.
